UNITED STATES PATENT OFFICE

107,332

DESIGN FOR AN EYECUP

Benjamin F. Conner, West Hartford, Conn., assignor to Colt's Patent Fire Arms Manufacturing Company, Hartford, Conn., a corporation of Connecticut

Application February 5, 1937, Serial No. 67,477

Term of patent 14 years

To all whom it may concern:

Be it known that I, Benjamin F. Conner, a citizen of the United States, residing at West Hartford, in the county of Hartford and State of Connecticut, have invented a new, original, and ornamental Design for an Eyecup, of which the following is a specification, reference being had to the accompanying drawing, forming a part thereof.

Of the drawing:

Fig. 1 is a plan view of an eyecup embodying my new design.

Fig. 2 is a front view thereof.

The stippled and unstippled portions of the

drawing are intended to represent differing colors, but not any particular colors. The design constituting the present invention is particularly characterized by the short and relatively thick but nevertheless distinct stem between the base and bowl portions, and by the elliptical shape of the base portion which shape generally conforms in horizontal outline to the shape of the bowl portion.

I claim:

The ornamental design for an eyecup as shown and described.

BENJAMIN F. CONNER.
